UNITED STATES PATENT OFFICE.

JOHN M. BARR, OF MILWAUKEE, WISCONSIN, ASSIGNOR TO THE LOUIS ALLIS COMPANY, OF MILWAUKEE, WISCONSIN, A CORPORATION OF WISCONSIN.

CONTRACTING APPARATUS.

Application filed October 23, 1922, Serial No. 596,429.

To all whom it may concern:

Be it known that I, JOHN M. BARR, a citizen of the United States, residing at Milwaukee, in the county of Milwaukee and 5 State of Wisconsin, have invented new and useful Improvements in Contracting Apparatus, of which the following is a specification.

This invention relates to contracting apparatus.

Such contracting apparatus is particularly adapted to perimetrically contract a rotor winding to bring the conductors thereof into position in the rotor slots.

15 The contracting apparatus may, of course, be employed for various other purposes.

An object of the invention is to provide efficient, strong and durable contracting apparatus which may be economically constructed and operated.

Another object is to provide a contracting apparatus which will prevent buckling of the appliance being contracted.

Other objects and advantages will herein-25 after appear.

In the drawings,

Fig. 1 is a transverse vertical section through the contracting apparatus with a rotor winding in position therein.

30 Fig. 2 is a top plan of the contracting apparatus.

Fig. 3 is a top plan of one of the plungers.

Fig. 4 is a side elevation of one of the plungers.

35 Fig. 5 is an end elevation of one of the plungers.

Fig. 6 is a perspective of several plungers with the heads thereof interconnected.

The contracting apparatus, in general, 40 comprises a plurality of contractors 1 so disposed as to enclose an appliance to be contracted, a carrier 2 for the contractors, and an actuator 3 to surround the contractors and move the same radially toward 45 the center.

The contractors may take the form of plungers 1 slidably mounted in radially disposed guideways in the carrier. The plungers 1 have jaws 4 to engage the appliance to be contracted.

50 The carrier 2 may take the form of an inner or movable ring.

The guideways for the plungers may be formed by milling radial slots in the ring 55 2 and covering the open side thereof with

an annular plate 5 fastened to the ring 2 by screws 6 or other fastening means.

The actuator may take the form of an outer or stationary ring 3 provided with a conical or inclined inner periphery 7 to 60 serve as a track on which the outer ends of the plungers 1 slide as the inner ring is forced down into the outer ring.

In order that the concentric relation between the spaced inner and outer rings may 65 be maintained, a plurality of inwardly extending centering lugs 8 are fastened to the outer ring 3 by screws 9 or other fastening means.

The outer end of each plunger 1 is inclined so as to co-operate with the inclined track 7, the inclination of both being the same.

Each plunger 1 has at its inner end a jaw 4 to grip the appliance to be contracted.

70 The jaws 4 are disposed to form an enclosure shown as substantially circular.

Each plunger is bifurcated from its jaw or inner end for more than one-half of its length, so the two parts 10 and 11 of the 80 jaw may yield toward each other as the plungers and jaws are forced toward the center.

The jaws 4 are provided with concave surfaces so as to fit the cylindrical end 85 surfaces of the circular surfaces of the appliances to be perimetrically shortened.

The outer edge of the jaw part 12 is provided with tongues 13 and grooves 14 which are arranged to mesh with alternately disposed grooves 15 and tongues 16 provided in the outer edge of the jaw part 17 of the adjacent plunger.

90 The outer ring 3 of the contracting apparatus is shown supported by ring 18 which may be made an integral part of the outer ring 3, if desired.

Pressure upon the inner ring 2 of the contracting apparatus may be applied 95 through a yoke 19 having a plurality of 100 depending legs 20, bearing on the inner ring.

When ever an end ring 21 of a rotor winding is to be contracted, the inner ring 2 of the contracting apparatus is raised 105 or drawn out of the outer ring 3 and the jaws 2 are moved outwardly until the end ring will fit within the encircling jaws.

110 The end ring is then placed in position within the encircling jaws, and the inner

ring 2 lowered, so that the outer ends of the plungers engage the track 7.

Pressure is then exerted through the yoke 19 on the inner ring 2 to force the same down into the outer ring. As the inner ring is forced down, the decreasing diameter of the inclined track causes the jaws to be forced inwardly to shorten the perimeter of the ring ring.

10 A convenient way to force the inner ring down into the outer ring of the contracting apparatus is to place the outer ring on the stationary base of a power press (not shown) and to exert pressure on the inner 15 ring by the movable plunger 22 of the press.

Should a power press having an upper stationary piston and a movable bed plate supported by a plunger which raises the same be employed, the inner ring of the contracting apparatus would then be held stationary while the outer ring would be moved with respect thereto.

20 The tongue and groove connection between adjacent jaws allows relative circumferential movement therebetween and provides a substantially continuous circular bearing for the appliance to be contracted.

This tongue and groove connection furthermore prevents buckling of the appliance 30 during the contracting thereof.

The invention set forth herein is, of course, susceptible of other embodiments and adaptations.

The invention claimed is:

35 1. Contracting apparatus comprising a carrier, a plurality of circularly disposed contractors on said carrier, and an actuator for said contractors, said contractors having a plurality of integral inner ends to form 40 circumferentially resiliently yielding contracting surfaces.

2. Contracting apparatus comprising a carrier, a plurality of circularly disposed contractors on said carrier, and a single 45 actuator for said contractors, adjacent contractors having sliding tongue and groove engagement.

3. Contracting apparatus comprising a 50 carrier, a plurality of circularly disposed contractors on said carrier, and an actuator for said contractors, said contractors having a plurality of integral inner ends to form circumferentially resiliently yielding contracting surfaces, the adjacent contractors having sliding tongue and groove engagement.

4. Contracting apparatus comprising relatively movable inner and outer concentric rings, the outer ring having a conical inner 55 face, a plurality of radially disposed contractors carried by the inner ring and having the outer ends thereof inclined to correspond to the angle of the conical face, a head on the inner end of each contractor, 60 and a tongue and a groove on said head, said 65

tongues and grooves on the heads of adjacent contractors interengaging to form a substantially continuous circular bearing surface.

5. Contracting apparatus comprising relatively movable inner and outer rings, the outer ring having a track on the inner face thereof inclined toward the center, spacers to maintain concentric relation between the inner and outer rings, and plurality of circularly disposed contractors carried by the inner ring and having the outer ends thereof inclined to correspond to the inclination of the track, the contractors being movable radially toward the center when either of the rings is moved axially toward the other.

6. Contracting apparatus comprising a carrier, a plurality of circularly disposed contractors on the carrier, the inner end of each contractor being bifurcated to allow the parts thereof to yield toward each other and the outer face being inclined, the inner end faces of adjacent contractors having tongue and groove engagement with each other, and an actuator having an inclined circular track to co-operate with the inclined outer face of the contractors to move said contractors radially toward the center when there is relative axial movement between the track and the carrier one toward the other.

7. Contracting apparatus comprising an actuator having an inclined circular track, an annular carrier concentric thereto, a plurality of circularly disposed contractors on the carrier, each contractor having the outer end thereof inclined to co-operate with the track so the contractors will move radially toward the center when there is relative axial movement between the track and the carrier one toward the other, the inner end faces of the contractors being grooved to form a substantially circular bearing surface, and sliding tongue and groove connections between adjacent contractors.

8. Contracting apparatus having in combination relatively movable inner and outer concentric annular members, the outer member having on the inner face thereof a track inclined toward the center, a plurality of radially disposed plungers movably supported by the inner member, the outer end of each plunger being inclined to co-operate with the inclined track, the inner ends of the plungers being grooved to form a substantially circular bearing surface and bifurcated to allow the parts thereof to yield toward one another, and slidible tongue and groove connections between adjacent contractors.

9. Contracting apparatus comprising relatively movable inner and outer rings, the outer ring having a track on the inner face

thereof inclined toward the center, spacers on the outer ring to maintain concentric relation between the inner and outer rings, and a plurality of circularly disposed

5 tractors carried by the inner ring, the contractors being movable toward the center when either of the rings is moved axially toward the other.

10. A contracting member for contracting apparatus having a plurality of adjacent end pieces integrally joined to provide laterally resiliently yielding contracting surfaces.

11. A contracting member for contracting apparatus having a plurality of adjacent

end pieces integrally joined to provide laterally resiliently yielding contracting surfaces, and having tongue and groove connections to connect with an adjacent contractor.

20

12. A contracting member for contracting apparatus having a plurality of adjacent end pieces integrally joined to provide laterally resiliently yielding contracting surfaces, and having an end face inclined to receive a wedging impulse from an actuating member.

25

In witness whereof, I have hereunto subscribed my name.

JOHN M. BARR.
